UNITED STATES PATENT OFFICE.

CHARLS J. BERTHEL, OF AKRON, OHIO.

STABILIZING DEVICE FOR USE ON AEROPLANES.

1,309,452.

Specification of Letters Patent. Patented July 8, 1919.

Application filed September 29, 1917. Serial No. 183,974.

To all whom it may concern:

Be it known that I, CHARLS J. BERTHEL, a citizen of Germany, residing at Akron, in the county of Summit and State of Ohio, have invented certain new and useful Improvements in Stabilizing Devices for Use on Aeroplanes, of which the following is a specification.

This invention relates to aeronautics and it is the principle object of the invention to provide a stabilizing device for use on aeroplanes, whereby the equilibrium of the same will be maintained while in flight, thereby tending to render the aeroplane rigid and preventing side slipping or tilting of the machine about a horizontal axis or from turning turtle.

Another and equally important object of the invention is to provide a stabilizer of the character mentioned whereby the center of gravity of the aeroplane will be lowered.

The foregoing together with additional advantageous details and arrangement of parts of the preferred embodiment of my invention will be clear from the specific description hereinafter contained, when read in connection with the accompanying drawings forming part thereof, wherein said embodiment of my invention is illustrated for the purpose of facilitating a full understanding of the present improvements.

In the drawings:

Figure 1 is a side elevation of an aeroplane having my improved stabilizer arranged thereon;

Fig. 2 is a section taken on the line 2—2 of the Fig. 1;

Fig. 3 is a vertical section through the stabilizer when in its inoperative or telescoped position, and

Fig. 4 is a front elevation of the aeroplane.

Similar characters of reference will refer to similar parts throughout the several views of the drawings.

Having more particular reference to the drawings, 1 represents an aeroplane in its entirety to which my improved stabilizer is applied.

The stabilizer includes a body formed of a plurality of telescopic sections generally indicated by the numeral 2, the said sections being substantially oval in cross section, and having the upper and lower ends of the same provided with flanges or shoulders 3 and 4.

As will be readily understood, upon refer-

ence to the Fig. 3, the shoulders 3 and 4 serve as means for limiting movement of the telescopic sections 2 when distended, the shoulders 3 upon the upper end of one of the said sections engaging with the shoulders 4 upon the lower end of the adjacent or receiving section. Rotatably mounted in suitable bearings 5 arranged in the lower end of the innermost telescopic section is a wheel 6, which, if desired, may be provided with a cushion tire or other suitable shock absorbing means.

The outermost telescopic section 2 is secured to the bottom of the body of the aeroplane, centrally thereof through the medium of a bracket 7, which bracket receives the same and is engaged therewith through the medium of bolts or other suitable fastening devices.

As means for collapsing the telescopic body, a cable 8 is provided and has one end thereof secured to the innermost section 2, while the other end of the same is engaged with a windlass or other form of winding drum 9, which drum is rotated through a power transmitting gear 10 connected thereto. In this connection, however, I desire to have it understood, that I do not confine myself to the use of any one form of means for raising or lowering the sectional telescopic body, that is, causing the various sections to be telescoped, but may employ any suitable form of mechanism, such as conditions or preference may dictate. It will of course be appreciated that the raising and lowering means whereby the body will be telescoped, is arranged at a point convenient to the operator or pilot of the aeroplane, in order that it may be readily operated without difficulty.

The sections 2 from which the telescopic body is formed may be and preferably are formed of strong light material, such as aluminum or one of its alloys.

In operation, the telescopic body is distended when an aeroplane carrying the same is in flight, by operating the raising and lowering means hereinbefore described, such operation being accomplished automatically. When landing, the body may be then telescoped by again operating the raising and lowering means, thereby so positioning the said body as to prevent its interference with the functioning of the landing gear of the aeroplane. The wheel 6, will serve as means for engaging a surface, and causing the tele-

scoping of the various sections 2 in the event that some difficulty arises in the raising and lowering means, thereby preventing the pilot from operating the same. In this way, perfect landing of the aeroplane will be permitted, irrespective of the condition of the raising and lowering means.

As will be readily understood by those skilled in the art, the stabilizer due to its 10 position upon the body of the aeroplane and due to the fact that the same depends therefrom lowers the center of gravity of the machine, and as a consequence, stabilizes the same when in flight, preventing the turning 15 turtle thereof, side slipping or the undue tilting of the aeroplane about a horizontal axis. Further, the stabilizer due to its exceedingly simple construction can be readily attached to practically any form of heavier 20 than air machine now used.

Manifestly, the construction shown is capable of considerable modification and such

modification as is within the scope of my claim, I consider within the spirit of my invention.

I claim:—
An aeroplane stabilizer, including a body formed from a plurality of telescopically engaged sections connected at one end to the bottom of the aeroplane and adapted to depend therefrom when in extended position, said sections of the body being substantially oval in cross section and having their opposite sides tapered forwardly and the front and rear portions thereof tapered to edges whereby to permit the passing of the same through air with but minimum resistance, a wheel mounted in bearings in the free end of the body, and means for effecting telescoping of the sections of the body.

In testimony whereof, I affix my signature hereto.

CHARLS J. BERTHEL.
